UNITED STATES PATENT OFFICE.

ALBERT T. MARSHALL, OF HARTFORD, CONNECTICUT, ASSIGNOR TO THE AUTOMATIC REFRIGERATING COMPANY, OF HARTFORD, CONNECTICUT, A CORPORATION OF NEW JERSEY.

TEMPERATURE CONTROL OF REFRIGERATING-COMPARTMENTS.

1,014,833.

Specification of Letters Patent.

Patented Jan. 16, 1912.

Application filed July 30, 1910. Serial No. 574,684.

To all whom it may concern:

Be it known that I, ALBERT T. MARSHALL, a citizen of the United States, residing at Hartford, in the county of Hartford and State of Connecticut, have invented certain new and useful Improvements in Temperature Control of Refrigerating-Compartments in Refrigerating Systems, of which the following is a specification.

10 The novelty of my invention resides in the varying of the brine level in a tank in which the refrigerating coils are placed and thereby interposing more or less of this heat conducting medium between the refrigerating coil and the air in the compartment so that for instance when the tank is filled with brine so that the refrigerating coil is completely submerged therein its full capacity will be utilized in cooling the brine 20 whereas if the brine level is lowered and only a small portion of the coil is submerged therein while the rest of it is insulated by pocketed and non-circulating air in the tank from the refrigerating compartment, only a 25 small portion of the coil will have effect on the compartment.

In the accompanying drawings I have illustrated how my invention may be reduced to practice.

30 In these drawings: Figure 1 is a longitudinal sectional elevation of three refrigerating compartments, and Fig. 2 is a transverse sectional elevation of compartment 12.

In these drawings 10, 11 and 12 represent 35 three refrigerating compartments which may be of varying sizes as shown. In the upper portion of each compartment is disposed a metal tank 13 adapted to contain brine or other suitable liquid with a low freezing 40 point. I prefer to use strong brine. The liquid is supplied to the tanks through main 16 which passes through all the chambers, the supply being controlled by hand valve 17. The brine may be drawn from each tank until 45 the desired level is reached by opening waste valve 18.

In each of tanks 13 is placed a refrigerating coil 14 which is supplied with refrigerant from the main 19. The refrigerating coils 50 14 are connected to the main 19 so that all the coils which are in operation are in series. For this purpose in the two ends of each coil near the point where they join the main 19 are disposed hand valves 4 and 5

and between the two coil ends a hand bypass 55 valve 1, 2 and 3 respectively is interposed in main 19. The refrigerant flows through main 19 in the direction as indicated by the arrow in Fig. 1. It will now be seen that when all hand valves 1, 2 and 3 in main 19 60 are closed, but valves 4 and 5 of each coil are open, refrigerant will pass through all three coils in series. If it is desired, for instance, to cut the refrigerant off from one of the coils for instance coil 14 in chamber 65 11, hand valve 2 is first opened and then valves 4 and 5 of coil 14 are closed. In consequence the refrigerant will pass directly through bypass valve 2 without passing through coil 14 in chamber 11. Thus 70 any of the chambers may be entirely cut off from refrigerant.

The operation of this system is as follows: Assuming that all three coils are open and their respective bypasses 1, 2 and 3 closed so 75 that the refrigerant passes through all the coils in series as described and assuming that each of the compartments 10, 11 and 12 should have different temperature; then brine valve 17 in each chamber is opened 80 and brine supplied to tank 13 until a certain level is reached. The brine being cooled by the refrigerating coils submerged therein will in turn, owing to the large surface of the metal tank, form a very effective cooling 85 medium for the compartment. Should the temperature in the compartment be still above the desired one, the brine level in that tank is raised by again opening hand valve 17 which submerges more turns of refrigerating coil 14 in this tank. Consequently a larger portion of the refrigerating coil becomes effective so that the temperature of the brine in this tank is lowered and also the brine level being raised in this tank a 90 larger effective cooling surface is exposed to the air surrounding the tank. If, on the other hand, the temperature of the compartment should be too low, brine waste valve 18 is opened and brine withdrawn from the 100 tank. Thus less turns of refrigerating coil 14 become effective in cooling the brine, the rest of the turns which are not submerged being most effectively insulated by the tank walls and the air contained therein from the 105 air contained in the compartment. Moreover now less of the metallic tank surface is cooled by brine and thus the effect of the

2
coil on the temperature of the compartment is lessened. I have found that in practice by thus changing the brine level in the several compartments a very satisfactory and 5 uniform refrigeration of the compartment may be obtained. If it is required to cut out the refrigeration in one or several compartments the refrigerant supply is cut off as described above.

10 What I claim is:

1. In a refrigerating chamber, the combination with a refrigerating coil disposed therein, through the whole length of which the refrigerant passes, and means for increasing and decreasing the effective area 15 of said coil, while its entire length is traversed by the refrigerant.
2. In a refrigerating chamber, the combination of a refrigerating coil for conducting 20 a continuous flow of refrigerant through its entire length and means for variably insulating portions of said coil from said chamber.
3. In a refrigerating chamber, the combination of a refrigerating coil for conducting 25 a continuous flow of refrigerant, a heat con-

ductor incasing said coil and having heat conductive connection with said coil and means for varying the extent of said connection with the coil.

4. In a refrigerating chamber the combination with a refrigerating coil disposed therein, a metal tank in said chamber in which said coil is disposed, said tank adapted to contain non-freezing fluid, and means 35 for varying the level of the fluid in said tank to submerge more or less turns of said coil therein.

5. In a refrigerating chamber the combination with a refrigerating coil disposed 40 therein, a metal tank in said chamber in which said coil is disposed, said tank adapted to contain brine, means for supplying brine to and draining it from said tank to vary the brine level and thus the number of 4 turns of said coil submerged in the brine at will to increase or decrease the effective area of said coil for the purpose set forth.

ALBERT T. MARSHALL.
